UNITED STATES PATENT OFFICE

2,463,013

FLUORESCENT LIGHTING EQUIPMENT

Gillson W. Beals, Meriden, and John Carulli, Branford, Conn., assignors to The Miller Company, Meriden, Conn., a corporation of Connecticut

Application September 29, 1945, Serial No. 619,290

10 Claims. (Cl. 240—51.11)

1
The present invention relates to fluorescent lighting equipment and is more particularly directed toward fluorescent lighting equipment adapted for use as an individual fixture or in continuous lighting equipment.

The present invention contemplates the provision of fluorescent lighting equipment wherein each unit length is in the form of a complete chassis which has an over all length the same as the nominal length of the lamps to be employed and carries all the structure and electrical parts necessary to provide a functioning piece of lighting equipment. This chassis employs a top plate and end plates, preferably welded together and shaped to form not only a housing for the ballast and wiring, but also supports for the lamp sockets and starter sockets (where used) and these parts may be completely enclosed by a cover which extends from one end plate to the other and from one side of the top plate to the other.

The present invention provides a chassis carrying all the equipment necessary for lamp operation and for its support from the ceiling or other overhead support and is suitable for employment in single units or continuous lighting equipment with such added ornamental end plates, covers and the like as will provide desired appearances for the complete equipment. The chassis itself is susceptible of mass production, assembly and test, and as it can be used with many forms of ornamental exteriors, it is possible to provide a very wide variety of lighting fixtures having the same basic and essential functioning parts.

Other and further objects will hereinafter appear as the description proceeds.

The accompanying drawings show, for purposes of illustrating the present invention, an embodiment in which the invention may take form, it being understood that the drawings are illustrative of the invention rather than limiting the same.

In these drawings:

Figure 1 is a fragmentary side elevational view of one end of the chassis, showing the lamps in position;

Figure 2 is a top plan view of the same;

Figure 3 is an end elevational view of the chassis illustrating a clamp for supporting it from a ceiling;

Figure 4 is a sectional view on the line 4—4 of Figures 2 and 3 illustrating two chassis united for continuous lighting equipment;

2

Figure 5 is a vertical sectional view on the line 5—5 of Figure 4;

Figure 6 is a section taken on the line 6—6 of Figure 7 showing a chassis in dotted lines and an end cover plate in normal position in full lines and in extended position in dot and dash lines;

Figure 6a is a fragmentary view illustrating in detail;

Figure 7 is an end view of a fixture with end cover plate in position; and

Figure 8 is a diagrammatic view illustrating various parts employed in an individual fixture of the bare lamp type.

The chassis of the lighting fixture employs a top plate 10, two end plates 11, 11 and a cover 12, all these parts being shown more in detail in Figure 8.

The top plate 10 extends for the full length of the fixture and has a flat upper portion 14, two longitudinally extending beads 15, 15 at the side, downwardly extending stiffening webs 16, 16, outwardly extending flanges 17, 17 and downwardly bent marginal edges 18, 18 preferably doubled on to one another for stiffness. Adjacent the stiffened edges 18, 18 the top member has downwardly facing seats 19, 19. The top plate 10 is somewhat wider than fluorescent lamp ballast 20, which is fastened in place by welding bolts 21. The plate may also be stiffened by longitudinally extending ribs 22, 22. The side walls 16, 16 may be provided with elongated holes 23 to facilitate ventilation.

This top plate which acts as a mounting pan may be supported by pipes such as indicated at 25 in Figure 1, or as indicated in Figures 2, 3 and 5, it may be supported by clamps such as 24 which engage the beads 15, 15. The spacing of the beads is preferably the same as that employed in the wiring channels of Patents 2,291,491, 2,291,492 and 2,321,099, so that the lighting units shown herein may also be supported from the same type of hanger.

The end plates 11, 11 are alike and have a generally semi-circular body portion 30. Each end plate has an upper flange 31 which fits on the top of the top plate 10 and also two flanges 32, 32 which extend over on to the flanges 17, 17 of the top plate. The flanges 31 and 32 are welded to the top plate and the length of the top plate is such that the over all length of the fixture from the outside of one end plate to the outside of the other end plate is the nominal length of the lamp, typically 48 inches. The configuration of the top plate imparts stiffness to this plate and affords vertically and horizontally spaced areas for

welding the end plate to it. These end plates are further stiffened by braces 31.

Each of the end plates 11 has, as here shown, four extensions 33 in the plane of the body of the end plate, each adapted to support a lamp socket or lamp holder 34. This type of lamp holder is of the type designed to be secured to a flat mounting plate or support with its extreme outer face in the plane of this support, as will be apparent from the drawings. The end plates are slotted adjacent the extensions 33 as indicated at 35, to accommodate the body of the lamp socket or holder and the material between the extensions 33, 33, is bent at right angles to the body of the end plate as indicated at 36. This material extends in between the lamp sockets so as to afford a closure between the sockets and from the sockets to the upper edge of the end plate. Each end plate carries a bracket 38 adapted to receive a pair of starter sockets 39.

The trough shaped sheet metal cover 12 has its upper edges 41 fitted inside the stiffening flanges 18 of the top plate and is held against the seats 19 by screws 42 held in place by split washers 42' and threaded into the lowermost extensions 36. The cover is apertured at 43 to permit the starters 43, 43 to extend down below it.

The top plate, end plates and cover above described are, together with the ballast, the sockets and wiring, adapted to form a complete serviceable chassis for a four lamp fluorescent lighting fixture whose over all length is nominal lamp length. This chassis may be used either in continuous lighting installations or for individual units. The end plates are provided with knock-outs 44 and the adjacent end plates are coupled together by a nipple 45 and nuts 46 as shown in Figure 4. This nipple provides a wire-way to carry the wires from one unit to the next.

When the chassis is for use in individual fixtures, various forms of ornamental constructions may be applied. One of these forms is shown in Figures 6 and 7. As an example of such a cover plate there is shown at 50 one made of sheet metal of the appearance shown in Patent No. 2,320,829. This end plate cover 50 is provided with a U-shaped strap 51, adapted to extend between the upper corners of the end plates 11 and adjacent the beads 15, 15. When the end plate cover 50 is in the inner position as indicated in Figure 6 in full lines, it is preferably held there by a screw 51' threaded into a tapped hole 54 in the end plate. A split washer 53 keeps the screw in place. When in this position the peripheral inner edge portion 55 of the end plate cover extends past the lamp sockets or holders and the adjacent ends of the lamps so that the ends of the lamps and the socket holders are concealed.

To make it possible to readily obtain access to the sockets for insertion or removal of lamps, it is merely necessary to loosen the screw 52' at one end of the unit and slide the end plate cover outwardly to the dot and dash line position of Figure 6 where it clears the lamp sockets. It is held in place by the prongs of the U-shaped member 51.

It will, of course, be apparent that a very wide variety of ornamental end plate covers may be secured to the chassis in this manner, it merely being necessary that they be designed to fit the chassis and accommodate the sockets and lamps. Such end plate covers may also be used to support louvers or diffusing equipment which surrounds all the lamps. Screw holes 55 in the end plates are provided for securing end plate covers permanently in place. Such constructions are illus-

trated in the application executed and filed concurrently herewith, Serial No. 619,306.

Since it is obvious that the invention may be embodied in other forms and constructions within the scope of the claims, we wish it to be understood that the particular form shown is but one of these forms, and various modifications and changes being possible, we do not otherwise limit ourselves in any way with respect thereto.

What is claimed is:

1. A body for a fluorescent lighting fixture employing rectilinear fluorescent lamps, said body having an over all length equal to nominal lamp length and comprising two vertical end plates 15 with their outer surfaces in parallel planes spaced an amount equal to nominal lamp length, a horizontal sheet metal top plate to which the end plates are secured, the end plates extending downwardly and each having a plurality of lamp socket supports disposed in the same plane as the outer face of the end plate, a trough shaped sheet metal cover extending from one edge of the top plate to the other and from one end plate to the other, means for detachably securing the cover to the end plates, and lamp sockets secured to the socket supports with their outer faces in the same plane as the outer faces of the end plates and projecting beyond the cover for supporting the lamps alongside the cover.
2. A lighting fixture body as claimed in claim 1, wherein the top plate has a generally flat upper central portion, longitudinally extending beads therealong for the reception of hooked fixture supports, a vertical stiffening portion below each bead and a horizontal flange outside each stiffening portion so that the outer edges of the flanges of the top plate are below the beads and spaced farther apart than the beads.
3. A lighting fixture body as claimed in claim 1, wherein the top plate has downwardly facing seats for the upper edges of the cover and downwardly flanged edge portions covering the upper edges of the cover.
4. A lighting fixture body as claimed in claim 1, wherein the lamp socket supports on each end plate are integral therewith.
5. A lighting fixture body as claimed in claim 1, wherein the end plates have flanges between the sockets and extending to the edges of the cover.
6. A lighting fixture body as claimed in claim 1, wherein the cover securing means includes inwardly bent bottom flanges carried by the end plates.
7. A lighting fixture body as claimed in claim 1, wherein each end plate carries a bracket spaced above the bottom of the cover and starter sockets are secured to the brackets, the cover having holes to admit starters to the starter sockets.
8. A lighting fixture for rectilinear fluorescent lamps comprising, a sheet metal top plate, a ballast carried by the top plate, two sheet metal end plates secured to the top plate with their outer faces spaced nominal lamp length, the end plates having a plurality of radial socket supporting extensions in the plane of the plate, fluorescent lamp sockets on the extensions, the end plates having flanges between the extensions and sockets, the sockets extending beyond the flanges, a trough shaped sheet metal cover extending from the flanges on one end plate to the flanges on the other end plate and from one edge of the top plate to the other edge, so as to form a completely enclosing body for the ballast.

and fixture wiring, means for securing the cover in place, and rectilinear fluorescent lamps extending from the sockets carried by one end plate to those carried by the other end plate.

9. A fluorescent lighting fixture end plate made of sheet metal and having a plurality of lamp socket supporting extensions radiating from and in the same plane as the body portion of the plate and integral filler flanges at substantially right angles to the plane of the plate and between the socket extensions, the flanges being spaced from one another an amount to accommodate lamp sockets carried in the extensions.

10. A fluorescent lighting fixture comprising a chassis which includes end plates carrying a plurality of fluorescent lamp sockets opposite one another, fluorescent lamps extending between the sockets, end plate covers disposed outside the end plates and extending outside the sockets and inwardly about the sockets and adjacent ends of the lamps to conceal the sockets and lamp ends and interfere with lamp insertion and removal, and means comprising elongated cover supports secured to the cover and longitudinally slideable along the chassis to sup-

port the covers in said position or displaced from the end plates to be beyond the sockets to facilitate lamp removal and insertion.
